METAL CONTAINER

Charles E. McManus, Baltimore, Md., assignor to
Crown Cork & Seal Company, Inc., Baltimore,
Md., a corporation of New York

Application March 14, 1934, Serial No. 715,537
Renewed December 17, 1936

1 Claim. (Cl. 220—66)

My invention relates to containers, particularly receptacles formed from relatively thin sheet metal and adapted for the retail distribution of milk and milk products. The container is characterized by having a closing end provided with an integral pouring spout and a detachable and replaceable sealing cap.

It has heretofore been suggested that milk and milk products may be packaged in metal containers, and this practice is carried on commercially in connection with condensed milks. As to the latter, a commercial tin can is employed having similar flat ends, and two or more punctures must necessarily be made in one end of the can, in order to permit the milk to pour. Thereafter, such punctures or openings necessitate that the milk within the container be exposed, which is frequently objectionable, as where but small portions of the contents are used from time to time.

There are definite problems involved in producing a receptacle of relatively thin sheet metal useful as a package for normal milk as well as condensed milk and having a pouring spout and separable sealing cap. It is desirable that the package be manufactured at small expense in order that it may be discarded after the contents have been exhausted. Also, it is necessary that the package be susceptible to filling in the usual manner without requiring alteration of existing filling machinery. It is a particularly important requirement of receptacles of this character that they possess the required strength and rigidity to withstand filling and closing or sealing operations of the container, as well as resist the shocks and jars to which the filled receptacles are subjected in normal transportation and handling.

For example, the container of the present invention is adapted for use following a procedure known as bottom filling; i. e., the top is applied to the container, thereafter the container is filled and then the bottom is applied. Under such practice, it is necessary that the top closing end be rigid to support the contents, and also strong enough to withstand the strains incident to application of the bottom after the container has been filled.

Somewhat similar arduous conditions prevail where the container is top-filled by means of suitable filling machinery and then capped with an automatic capping apparatus. The container of this invention may be satisfactorily used with such procedure.

Again, it is customary to rapidly move the filled and unfilled containers through the plant by machinery and the subsequent handling and

transportation of the product is accompanied by much rough treatment. This is evidenced by the breakage of glass containers in large numbers at the present time. Consequently, the value of a metallic receptacle which is resistant to distortion and thoroughly liquid proof is readily understood.

An important feature of the present invention resides in having the closing end constituting the top of the container manufactured as a unit. Such container top comprises a metallic flange which is relatively flat, and which has a preferably centrally disposed integral pouring spout adapted to receive the detachable closure cap. The pouring spout is formed by drawing the metal centrally of the flange upwardly along curved lines producing a continuous concavely curved upstanding wall, defining an opening, extending entirely above the plane of the flange.

The wall of the spout is concavely curved from end to end and is flared inwardly with respect to the flange at its lower end, thereby producing a relatively enlarged entrant opening. The spout is continuously curved inwardly, and then outwardly at the upper free end so as to produce an outwardly flared portion of relatively reduced diameter. The radius of curvature of the inwardly flared portion of the spout or wall and the length of its arc are greater than the radius of curvature and the arc of the outwardly flared free or pouring end of the spout or wall. This is important, in that both the flange and spout are thereby stiffened and strengthened. Briefly, by reason particularly of the relatively long radius of curvature of the inwardly flared portion, forming in effect a continuous arch, the flat, circumferential area of the flange is reduced relative to the arched wall and rigidified. The entrant portion of the spout opening, moreover, is given an enlarged diameter which is gradually reduced along arch-like lines to the minor diameter of the spout wall. The outwardly flared upper portion of the spout is continued from this minor diameter on a curve which is of less radius than the radius of the inwardly flared portion, so that this end which receives the finish and to which the cap is applied is strengthened and partially extends over the inwardly flared portion of the spout wall.

I have found that by giving the wall or spout a concave curvature from end to end with the lower end thereof merging with the flange on a radius of greater diameter than the radius of curvature of the outwardly flared pouring end of the spout forming a continuous arch, that a closure cap may be applied by means of

automatic machinery and prised off without distorting the flange or destroying either the seal or the utility of the spout. Moreover, this rigidifying of the closing end of the container enables 5 the closing end unit consisting of the flange, integral spout and sealing cap to be applied to the body portion of the container with automatic machinery and also allows the receptacle to be reversed and bottom-filled without injuring the 10 seal or the closing end or the container during the filling or the subsequent application of the bottom. Also, by forming the wall spout along continuous curved lines, i. e., concavely curved from end to end, the flange and spout are 15 strengthened to likewise withstand the strains incident to the rough treatment encountered in handling and transporting of the filled containers.

The flange and wall are smooth and unobstructed so that there are neither weakened areas 20 or creases in which accumulations of product may collect.

The free, outwardly flared end of the wall or neck of the top is preferably folded over to 25 stiffen the edge of the wall and also to form a finish for receiving a detachable sealing cap. For example, I use an ordinary crimped or crown cap which will fit over the folded portion or bead and provide an efficient tight seal. Also, I use 30 a cap wherein the flange is pressed or ironed over the flared portion and bead of the spout or neck to form the seal.

I find that by reason of the rigidity of the closing end or top and its integral upstanding wall 35 a detachable cap, such as a crown cap or a pressed-over cap, may be applied by suitable capping machinery, and will efficiently seal the container during the filling and closing operations, as well as remain fluid-tight, notwithstanding unusual handling conditions and transportation.

Preferably the detachable cap will be one of sufficient flexibility that it may be reapplied continuously to the container until the contents are exhausted, and at all times maintain the contents sealed.

The top closing end unit, therefore, will comprise the flange with its integral upstanding wall or pouring opening and the detachable cap applied thereto. This top or closing end will be 50 manufactured as a unit and have the cap and flange suitably decorated, and may be supplied independently of the receptacle body portion. No additional machinery is required to apply the top to the body portion, the closing end being 55 completely assembled in every particular ready to be affixed to the body.

While the container of the present invention is particularly useful in connection with milk or 60 milk products, as a package therefor and will be of a size convenient for retail merchandizing, it will be understood that other liquid articles as well as dry or substantially dry materials may be similarly packaged and the container may have 65 any desired size.

Referring to the drawing,

Figure 1 is a view showing the container of the present invention with the parts disconnected;

Figure 2 is an elevation of the container of the 70 present invention with the closing end or top applied and with the container in reverse position for bottom filling with the bottom disconnected;

Figure 3 is a sectional view showing the container top applied to the body portion of the container, the latter being broken away; and

Figure 4 is a detail view in side elevation of a top or closing end unit.

The receptacle comprises a body portion 10, a top closing end unit 11, including a detachable closure cap 13 affixed to the top and assembled 5 therewith, and a bottom 12.

All of these parts are preferably made of relatively thin sheet metal and the container may be circular as shown, or square, hexagonal or any desired angular form.

The body portion 10 will be folded in the usual manner to produce a cylinder having its free ends joined by a seam 14. The upper and lower edges of the cylinder are provided with the usual flanges 15 and 16 for engagement with flange portions 15 22 and 26 on the top closing end 11 and bottom 12 respectively. These parts are all united in any suitable conventional manner.

The metal forming the various parts of the container may be externally decorated as desired 20 and internally will be thoroughly aseptic so as to reduce to a minimum any possibility of contamination.

The top closing end 11 is produced as a unit, as 25 best shown in Figure 4. This unit comprises a flange 17, as shown in Figures 1 and 3, which is relatively flat and of a contour to close one end of the body portion 10. Preferably, the metal at the central portion of the flange is produced by a suitable drawing operation into an upstanding continuous neck or wall defining an opening and forming a pouring spout adapted to receive a detachable closure. This neck or wall is concavely curved, i. e., drawn along curved lines from end to end, and as shown at 18, 30 inwardly flared with relation to the flange 17 to merge therewith. By drawing the metal of the flange, the neck or wall can be completed by a single operation and of particular importance the flange 17 is stiffened and strengthened. The 35 neck or wall is continuously curved inwardly as at 19 along arch-like lines and at its free end is flared outwardly as at 20. By producing a concavely curved neck or wall, this latter is likewise stiffened and reinforced. A portion of the metal 40 at the flared free end of the neck or wall is folded or rolled inwardly to form a bead 21, whence the neck is provided with a finish for receiving the sealing or closure cap 13 and likewise the neck is thickened and strengthened. While I have indicated the bead as being in the form of a tube, the metal may be folded to lie flat against the 45 wall of the neck and may be either in-folded or out-folded.

It will be noted that the neck is concavely 55 curved from end to end, and that at its lower end adjacent the flange it is inwardly flared and arch-like and at its outer end outwardly flared, the neck being curvilinear in cross section. The curvature of the inwardly flared portion 18 is on 60 a radius greater than the radius of curvature of the outwardly flared portion 20. The arcuate dimension of the inwardly flared portion 18 is greater than the arc of the outwardly flared portion 20 and the diameter of the outwardly flared portion is less than that at the entrant portion of the spout or wall. The diameter of the spout or wall is gradually decreased on an arch-like curve from said entrant portion to a minimum diameter, forming a continuous arch, and continued on a 65 curvature of increased radius from said minor diameter to form the outwardly flared portion 20. In this manner, an enlarged entrant opening is formed in the wall or spout and the circumferential area of the flat portion or flange 17 is re- 75

duced and rigidified. This latter is particularly true because of the magnitude of the inwardly flared portion relative to the area of the flange 17, whereby the flange is fortified against distortion by the continuous arch-like wall of the spout. For example, the diameter of the flange 17 for a particular container prior to affixing the unit to the can body will be substantially three and one-quarter (3 1/4) inches and the largest 10 diameter at the entrant opening of the spout will be two and one-half (2 1/2) inches. In this manner substantially sixty to seventy per cent of the metal of the closing end is utilized in forming the spout and without sacrificing the 15 strength of the flange, but rather rigidifying the same. This is due to the continuous arch provided by the inwardly flared portion of the spout wall. Likewise, the spout is rigidified and the outwardly flared portion which may be formed 20 as a finish to receive a detachable closure of the crimped or pressed-on type is strengthened.

The dimensional characteristics and contour of the pouring spout or wall, it will be observed, are of vital importance, in that the application 25 of a crimped or pressed-over cap may be applied to the spout without distorting or collapsing the same or the flange 17, or the container body, and by the usual capping machinery. Moreover, the outwardly flared portion partially overlies the 30 inwardly flared area of the wall opening, so that when the cap is applied there is presented a space for the insertion of a prizing tool to remove the cap. Also, the provision of a strengthened 35 closing end and spout is important where bottom-filling and closing procedure is resorted to, since the top closing end in such case will be staunch enough to withstand the shocks and jars incident to filling and applying the bottom closing end to the body portion.

40 It will also be noted that both the flange and the neck are free of indentations and are smooth and continuous. This renders the closing end top 11 strong and resistant to the various strains to which the container is subjected and, more- 45 over, eliminates the possibility of accumulations collecting interiorly of the container about the outlet thereof.

It is also to be noted that the entrant area 50 of the opening defined by the flared portion 18 is relatively enlarged, insuring that all of the contents will be discharged from the container.

The closing end unit 11 (Figure 4) includes the sealing cap 13 which is assembled therewith and may be a crimped cap, as shown in Figure 4, or 55 a pressed-over cap having its flange ironed around the bead 21 and flared portion 20, as shown in Figure 3. If desired, the finish of the neck or spout may be made to receive a cap having inward projections on its skirt, such as a lug cap, 60 or the finish may have a continuous thread to receive a closure, the skirt of which is formed with a similar thread. The cap preferably has a flat face 23 so that when the container is reversed for the bottom filling operation, as shown 65 in Figure 2, it will lie flat on the usual conveyor. The sealing cap 13 is detachable and of such character that it may be removed and reused until the contents are exhausted. In prying off

the cap the wall or neck is somewhat distorted, as will also be true of the cap, but this distortion normally will not interfere with the reforming of the seal with the same cap, although it very definitely indicates that the container has been 10 opened and therefore it will now be impossible to use the container as a new package without detection. This is important, because it is one of the purposes of the invention to provide a container which must be discarded after it has been used once.

The sealing cap 23 will comprise the usual skirt 24 and sealing liner 25 as shown in Figure 3. While I have referred to a cap which may be pried off, any other suitable cap may be used, 15 but I prefer one which is capable of being reapplied until the contents are exhausted and which will form a satisfactory seal at all times.

The unit 11 therefore comprises the flange 17 which is stiffened and reinforced by the arch-like 20 continuous wall of the spout, the concavely curved neck or wall 18, 19, 20, forming a pouring spout adapted to receive a sealing cap, which is likewise 25 rigidified, and the closure cap 13, all assembled as a complete article. This assembly will be 30 manufactured in required size and suitably decorated if desired so that the units will be available to any purchasers who are provided with metal container making machinery. In such cases, the closing end top 11 is applied without change or 35 alteration in such machinery.

Referring to Figure 2, I have illustrated the body portion 10 having the closing end unit affixed thereto and the container in reversed position preparatory to bottom filling. The reinforced 35 structure of the unit 11 is such as to permit bottom filling to take place without danger of distorting either the closing end or the body portion. After the container has been filled the bottom 12 is applied in the usual manner and 40 the product is ready for transportation.

I claim:

As a new article of manufacture, a package comprising a sheet metal body of substantially tubular form, a bottom wall secured to said body, 45 a top wall secured to said body, said top wall having a substantially central pouring and filling opening relatively small with respect to the body and surrounded by a neck drawn from said top wall, the neck adjacent its top being deflected 50 outwardly to form an external circumferentially extending shoulder providing a locking shoulder for a crown cap and the edge of the top wall around said opening being curled into a continuous bead and folded at its raw edge to form 55 an inwardly projecting sealing lip to coact with a crown cap and provide radial resistance to the crimping pressure required for applying a cap, said top wall sloping downwardly and outwardly 60 away from said locking shoulder toward and to the body whereby to transmit axially-directed crowning pressures to the body wall along lines uniformly distributed around and at angles to the container axis, and a crown cap having a crimped continuous skirt forced into interlocking 65 engagement with said external shoulder.

CHARLES E. McMANUS.
